UNITED STATES PATENT OFFICE.

JOHN JONES, OF LITTLEBOROUGH, AND JESSE RIGG, OF ROCHDALE, ENGLAND.

PACKING DEVICE FOR PISTONS, PISTON-VALVES, AND THE LIKE.

No. 924,789.

Specification of Letters Patent. Patented June 15, 1909.

Application filed December 14, 1908. Serial No. 467,393.

To all whom it may concern:

Be it known that we, JOHN JONES and JESSE RIGG, subjects of the King of Great Britain and Ireland, and residents of Littleborough and Rochdale, respectively, both in the county of Lancaster, England, consulting engineer and engineer and machine-maker, have invented certain new and useful Improvements in Packing Devices for Pistons, Piston-Valves, and the Like, of which the following is a specification.

This invention relates to improved means for enabling the pistons of steam or other engines, pumps and the like, to be kept steam or liquid-tight in the cylinders or barrels in which they work, the invention being equally applicable to piston valves and, in fact, to pistons of any kind.

It refers to that class of device chiefly consisting of inner and outer ring segments bearing against each other as a result of pressure exerted by one or more springs, the object being to provide an improved arrangement of spring device for use in conjunction with the inner segments.

In the hereinbefore mentioned application for Letters Patent filed by us we described a combination of separated inner segment rings operating in conjunction with outer segment rings or packing rings having tenon joints, certain spring devices and screws being employed in connection with such to form the complete packing arrangement.

Our invention particularly relates to this class of device and will be fully described with reference to the accompanying drawings in which,

Figure 1 is a plan of a piston packing constructed in accordance with our present invention, Fig. 2 side elevation of same, Fig. 3 partial sectional side elevation, Fig. 4 partial plan showing a slightly modified arrangement, Fig. 5 side elevation showing the slide device hereinafter referred to for carrying the springs, Fig. 6 plan showing a modified arrangement, Fig. 7 side elevation of same, Fig. 8 partial elevation of same and Figs. 9 and 10 plan and elevation of a further modification.

In the foregoing drawings similar letters indicate corresponding parts and from these it will be seen that our invention consists in providing each end of the inner segment rings *a* with suitable slideways *b*. These may be formed so as to give a channel section in plan or may be arranged to have an

outstanding projection or projections, preferably of a parallel character, though, in end elevation, the sides *c* of the channel or the projection or projections may converge so as to present a wedge-shaped groove or a wedge-shaped projection or projections. In conjunction with slide-ways or projections so formed we employ spring pressure devices adapted to be easily slid into and out of position between the ends of the segments, such devices consisting of brackets *d* adapted to fit one within the other with their ends *e* formed to fit in or on the slideways or projections formed in the segments.

The parts of the bracket which slide one within the other preferably consist of two tubes *f*, those on one bracket having an internal diameter corresponding to the diameter of those on the other bracket. The tubes on the latter may, however, be replaced by solid pins of the same external diameter. Mounted on the external or larger tubes, of which there are two pairs in connection with each pressure device and in large pistons sometimes more than two, are spiral springs *g* adapted to exert pressure endwise so as to force the brackets *d* against the segments and thereby put pressure on the outer ring or packing segments *h* which come directly in contact with the cylinder wall in which the piston works. By employing two or more sets of springs between each of the inner segment joints, equal pressure is given to the packing rings *h*, transversely of them, so as to keep them in perfect alignment with the cylinder wall.

i indicates bolts or studs preferably the former, passed through both the outer and inner segments and *j* are nuts adapted to keep the two segments together at or about centrally between the tenon joints *k* such as were previously described in our former patent.

In the partial plan shown in Fig. 4 we arrange along the front side of the spring device a plate *m* adapted to fit in additional grooves *n* formed in the ends of the segments *a*. The plate has a sliding fit in the grooves so as not to restrict the circumferential movement toward or from each other of the segments. This plate is for the purpose of entirely covering the joint between each two sections of segments and so render them more completely steam or liquid tight. The arrangement of segments just described and the method of joining them enables the outer

rings *h* to be entirely dispensed with as in Fig. 4.

In Figs. 6 to 8 a modification of the same idea is illustrated. In this case the inner 5 faces of each pair of segments where they join together are formed flat at *o* and against this flat surface is secured a bracket *p*, a stud or bolt *q* being employed for the purpose, such stud being passed through the end of 10 one of the joining segments only. One end of the bracket *p* has a slidable fit in a groove *r* formed in the segment while the other end of the bracket has formed in it a groove or slideway *b* or is provided with a 15 projection of a similar character to those already described. The spring devices employed in connection with this form of packing are exactly the same as those previously referred to while the bracket *p* takes the 20 place of the plate *m* shown in Fig. 4.

In the modification illustrated in Figs. 9 and 10 the outer segment rings *h* are dispensed with. Like letters indicate similar parts to those in the other views. In this 25 case two sets of segments *a* are employed forming two complete rings, one upon the other. The several joints of each ring are arranged to overlap those of the others on their plane faces but otherwise their construction 30 is similar to that in Fig. 4, as is also this arrangement of plates *m* and springs *g*. In addition to the latter, pins or projections *s* are formed on the segments to hold in position springs *t*, which have their axes parallel 35 to that of the piston rod. By these latter means the two sets of complete rings may be pressed toward the flange on the piston block and junk ring, respectively. Further the inner segments in all cases may be of channel 40 shape in transverse section so that the connecting web or side which presses against the inner surface of the outer segments or against the cylinder wall may be made thinner, while strength is retained by the webs.

45 The arrangement of double spring pressure and segment devices hereinbefore described

makes a most admirable packing device for the purposes referred to which is capable of exerting equal and constant pressure throughout the whole circumference and depth of the 50 packing rings against the internal wall of the cylinder in which the piston works and consequently equal wear of both working surfaces occurs.

We are aware that it has previously been 55 proposed in pistons to employ T-shaped short spindles having swiveling heads, the spindles telescoping into one another and supporting on them a compression spring while the heads bore against lugs on an inner expansion ring 60 bearing against the outer or packing rings. One telescoping spindle only with its spring was employed opposite each joint of the expanding ring. We do not claim any such arrangement.

65 What we claim as our invention and desire to secure by Letters Patent is:—

1. The combination, with piston segments provided with sockets on their adjacent end portions, of telescopic guides provided with 70 brackets at their ends which are slidable in the said sockets, and springs encircling the said guides and pressing the said brackets apart.

2. The combination, with piston segments provided with sockets on their adjacent end portions, of telescopic guides provided with brackets at their ends which are slidable in the said sockets, plates overlapping the joints of the said segments and bearing 75 against each pair of brackets, and springs encircling the said guides and pressing the said brackets apart.

In testimony whereof we have hereunto set our hands in the presence of two wit- 85 nesses.

JOHN JONES.
J. RIGG.
